UNITED STATES PATENT OFFICE.

NILS E. BORCH, OF BERKELEY, CALIFORNIA.

RADIOFREQUENCY TRANSFORMER.

Application filed July 15, 1922. Serial No. 575,308.

My invention is an improvement in radio frequency transformers.

The object of my invention is to provide a transformer which is simple in construction, and which has a core which also serves as a screen.

Another object of my invention is to provide a transformer which is inexpensive to manufacture, and efficient in operation.

10 Referring to the drawing which forms a part of this specification—

Fig. 1 is a perspective view of my transformer with the casing removed.

15 Fig. 2 is a transverse sectional view of my transformer.

Fig. 3 is the wiring diagram of a radio circuit embodying my invention.

Referring more particularly to the drawing:

20 The numeral 1 indicates a sleeve, upon which is wound a primary coil 2 and a secondary coil 3. Leads 4 extend from the primary coil 2, and leads 5 extend from the secondary coil 3.

25 A material 6 consisting of plaster of Paris and fine steel filings mixed therein, completely covers the sleeve 1 and also fills the bore thereof, thus forming a core. The material 6 is a conductor and serves as a screen

for the inductive circuits set up by the coils 30 2 and 3.

A sleeve 7 surrounds the material 6, and has heads 8 and 9. Binding posts 10 are secured to the head 8, and posts 11 are secured to the head 9. Primary leads 4 are 35 secured to the posts 10 and secondary leads 5 are secured to the posts 11.

My transformer may be used in any of the well known radio receiving circuits as is illustrated in Fig. 3. The primary coil 40 2 is placed in series with the grid of an audio tube 12 and a battery 13, and the secondary coil 3 is placed in series with the resistance coil of an audio tube 14 and with a variometer 15. A battery 16 is wired in 45 series with the incandescent filaments of tubes 12 and 14 and the aerial (not shown) is attached to the resistance coil of the tube 12 and to one lead of the secondary coil 3.

Having described my invention, I claim:— 50

A radio frequency transformer comprising a sleeve, primary and secondary coils wound on said sleeve, and a conductive material consisting of plaster of Paris and steel filings, surrounding said sleeve. 55

In testimony whereof I affix my signature.

NILS E. BORCH.
